CABLE SPLICING COMPRESSION SLEEVE

Carroll A. Badeau, Westfield, N. J., assignor to The Thomas & Betts Co., Elizabeth, N. J., a corporation of New Jersey

Application December 2, 1957, Serial No. 48,749

Term of patent 14 years

(Cl. D26—1)

Fig. 1.

Fig. 2.

Fig. 1 is a view in perspective of a cable splicing compression sleeve showing my new design; and

Fig. 2 is a longitudinal sectional view of the same.

The opposite side and end face of the compression sleeve not shown are substantially mirror images of those shown.

I claim:

The ornamental design for cable splicing compression sleeve, as shown and described.
